US0D1056674S

(12) **United States Design Patent** (10) **Patent No.:** **US D1,056,674 S**
(45) **Date of Patent:** **** Jan. 7, 2025**

(54) **DEADBOLT THUMB TURN BLOCKER**

(71) Applicant: **Jingliang Zhang**, Guangdong (CN)

(72) Inventor: **Jingliang Zhang**, Guangdong (CN)

(**) Term: **15 Years**

(21) Appl. No.: **29/930,993**

(22) Filed: **Mar. 4, 2024**

(51) LOC (15) Cl. **08-07**

(52) U.S. Cl.

USPC **D8/339**

(58) **Field of Classification Search**

USPC D8/331, 339, 341, 342

CPC E05B 9/02; Y10T 70/00; Y10T 70/40

(57) **CLAIM**

The ornamental design for a deadbolt thumb turn blocker, as shown and described.

DESCRIPTION

FIG. 1 is a perspective view of the deadbolt thumb turn blocker showing my new design;

FIG. 2 is a rear perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the use state thereof. The broken lines depict portions of the deadbolt thumb turn blocker that form no part of the claimed design.

1 Claim, 9 Drawing Sheets
